DAVENPORT

Filed Sept. 13, 1923

INVENTOR.

JOSIAH A. DEWEY.
BY Joseph B. Gardner
ATTORNEY.

UNITED STATES PATENT OFFICE.

JOSIAH A. DEWEY, OF OAKLAND, CALIFORNIA.

DAVENPORT.

Application filed September 13, 1923. Serial No. 662,440.

To all whom it may concern:

Be it known that I, JOSIAH A. DEWEY, a citizen of the United States, and a resident of Oakland, county of Alameda, and State of California, have invented a new and useful Davenport, of which the following is a specification.

My invention relates to a davenport, that is, a structure combined with a bed frame 10 that may be folded to form with said structure a settee or unfolded to form the equivalent of a regular bedstead.

Davports as usually constructed, include large and substantial side frames at the 15 opposite ends of the structure. These side members or frames, although adding to the appearance and comfort of the davenport while the latter is used as a seat, form undesirable side obstructions when the davenport is in use as a bed. It is one of the 20 objects of my invention, therefore, to provide a davenport which will have large side members when the davenport is used as a seat, but when formed into a bed the obstructing portions of said members will be 25 automatically removed and besides serve a useful function.

Another object of the invention is to provide a davenport which affords the use of 30 a full-sized double bed, but which nevertheless may be moved through an ordinary sized doorway without requiring the davenport to be taken apart in any way.

A further object is to provide a davenport 35 in which the entire front portion of the supporting frame or box is made of solid material.

The invention possesses other objects and 40 features of advantage, some of which, with the foregoing, will be set forth in the following description of the preferred form of my invention which is illustrated in the drawings accompanying and forming part of the specification. It is to be understood 45 that I do not limit myself to the showing made by the said drawings and description, as I may adopt variations of the preferred form within the scope of my invention as set forth in the claims.

50 Referring to said drawings:

Figures 1 and 2 are transverse sectional views of the davenport in position for use

as a bed and seat respectively. For the purpose of clearness the upholstery is omitted from the drawing. 55

Figure 3 is a fragmentary plan view of one of the side portions of the davenport in use as a bed.

Figure 4 is a fragmentary sectional view similar to Figure 2, showing a slightly 60 modified construction.

The davenport of my invention as illustrated in Figures 1 to 3 of the drawings comprises a supporting frame 4 having a back 5, front plate 6, and side members 7. 65 Arranged in the supporting frame is a foldable bed frame 8 formed of a plurality of sections 9, 10, 11 and 12 which are pivotally connected together. Sections 10, 11 and 12 will be referred to as head, intermediate, and 70 foot sections, respectively. The sections are preferably provided with side rails 13 across which is stretched a fabric spring 14. One of the sections which shall hereafter be referred to as the head section 10 is secured 75 to the sides 7 by means of parallel links 16 which serve to hold the section horizontally disposed in its various positions. When the davenport is in use as a seat, the section 10 is in a lowered position and 80 rests on a support 17, whereas when the davenport is in use as a bed, the section 10 is in an elevated position and aligned with the other sections. The adjacent ends of the rails of adjoining sections are prefer- 85

ably so constructed that when the bed frame is folded the adjoining sections will be disposed at right angles, while in the extended position of the bed frame, the sections will be held in horizontal alignment. As shown 90 in Figure 2 when the bed frame is folded the sections 9 and 11, which are of the same length, are opposite and parallel to each other, and the section 12, which I term the foot section, is parallel to and overlies the 95 head section 10, a stop 15, being preferably provided on the sides 7 to support the section adjacent its outer end when so disposed. The section 12 is preferably made shorter than section 10 so that in the folded position of the bed frame a gap is formed between the outer end of the foot section and section 9, a head board 18 fixed to the supplemental head section 9 being adapted to fit 100

across said gap. It will be noted that the bed frame when folded, lies considerably elevated from the floor, thus insuring sanitary conditions.

5 Means are provided for causing the head section to move upwardly and forwardly when the bed frame is extended. Fixed to the intermediate section 11 which connects the head and foot sections is an arm 21
10 which extends longitudinally of section 11 and is provided on its outer end with a roller 22 which is arranged to travel in a vertical guideway 23 provided on the inner side of member 7. With the roller thus disposed in the guideway, the unfolding movement of the bed frame, particularly the section 11, will serve to elevate the head section and place it in horizontal alignment with the others. By means of a link 24 connected to the side members 7 and section 9
15 the latter is caused to automatically move from vertical to horizontal position or vice versa when the head section 10 is respectively moved from elevated to depressed position or from depressed to elevated position.
20

It will be noted by referring to Figure 2, that the bed frame when folded lies rearwardly of the vertically disposed front plate 6 and below the top 26 thereof. However, it will also be noted by referring to Figure 1, that the bed frame is arranged when extended to lie over said plate but in a horizontal plane below the top of the plate as positioned when the frame is folded.
25

30 Means are therefore provided for causing the plate to be automatically moved to such position as will prevent its interference with the proper positioning of the bed frame when the latter is moved to extended position. In the present embodiment of the invention the foregoing is effected by hinging the plate adjacent its lower edge for movement about a horizontal axis, and by connecting the plate to the section 10,
35 the latter connection being preferably effected by means of a link 28. It will thus be evident that as the bed frame is extended and the head frame is moved accordingly, the plate will be swung outwardly and downwardly and will not interfere with the movement and positioning of the latter, and on the other hand when the bed frame is returned to its folded position the plate will be returned to its vertical position.
40

45 As hereinbefore stated, the present invention provides means whereby the davenport will have complete and substantial appearing side members when the davenport is in position as a seat, but when the davenport is in position as a bed such portions of the said members as would obstruct the sides of the bed frame are removed therefrom. The said obstructing portions of the side members usually include the arms 29
50 and the portion 30 adjacent and below the

55 arms. In accordance with my invention said obstructing portions are formed separate of the side members and are attached to the foot section 12 of the bed frame. In this manner when the bed frame is 70 folded said portions will appear as a part of the side members, whereas when said frame is extended, said portions will be entirely removed from the side members and will be positioned under the foot frame, 75 said portions incidentally forming legs for the frame when so positioned. It will now be clear that when the mattress and bed clothes (not shown) are on the extended bed frame, the sides of the bed will be for the most part unobstructed, and that the foregoing advantage is accomplished without sacrificing the appearance of the davenport when used as a seat.
80

Also fixed to the foot section 12 is the 85 seat frame 31 which is hinged to the outer extremity thereof. By being thus mounted the seat frame will swing downwardly below the fabric spring when the bed frame is extended, thereby preventing the seat frame from interfering with the functioning of the spring. Extending across the top of the davenport at the back, is a top plate 30 which is hinged at the rear end 90 so that it may be swung backward over the back 5 if desired.
95

In order that the weight of the foldable bed frame will not impair the ease of operation thereof, a counter-balancing 100 spring 33 is preferably secured at its opposite ends to the side members 7 and an arm 34 fixed to the section 10. The sections 10 and 11 are provided with pivotally mounted cross bars 35 and 36 which serve to resist inward displacement of the side rails.
105

110 In Figure 4 is shown a slightly modified form of the invention. In this embodiment the back member 40 and side members 41 extend upwardly to about the height of the seat. In this manner when the bed frame is extended and the mattress arranged thereon, no obstruction whatever will appear at the sides.
115

I claim:

1. In a davenport, a supporting frame, a foldable bed frame comprising a head section pivotally attached to said supporting frame for simultaneous movement vertically and horizontally, a second section pivoted to the first, a substantially vertical guideway arranged on said supporting frame, and an arm extending longitudinally from said second member and provided with a roller at its outer end arranged to travel in said guideway from one end to the other when said bed frame is changed from folded to extended position and vice versa.
120

2. In a davenport, a supporting frame, a foldable bed frame comprising a head sec- 130

tion mounted in said frame for vertical and horizontal movement, a second section pivotally connected to the first, an upwardly extending guideway fixed with respect to the frame, and means carried by said second section outwardly of and beyond the pivot point thereof arranged to engage said guide-

way whereby upon movement thereof along said guideway said pivot point will be displaced horizontally.

10

In testimony whereof, I hereunto set my hand at Oakland, this 25th day of August, 1923.

JOSIAH A. DEWEY.
